PICTURE PROJECTING MACHINE

Jack M. Miller, Chicago, Ill., assignor to Paromel Electronics Corp., Chicago, Ill., a corporation of Illinois

Application January 23, 1957, Serial No. 44,573

Term of patent 7 years

(Cl. D61—1)

Fig. 1.

Fig. 2.

Fig. 3.

Fig. 1 is a perspective view of a picture projecting machine showing my new design;

Fig. 2 is a rear perspective view thereof; and

Fig. 3 is a cross-sectional view thereof, taken on line 3—3 in Fig. 1, with the hinged portions of the top in opened position.

A portion of the drawing figures is diagonally lined to indicate transparency.

I claim:

The ornamental design for a picture projecting machine, as shown and described.
